BOTTLE FILLING VALVE

Wilfrid Lemire, Montreal, Quebec, Canada, assignor to Charles Gurd and Company, Limited, Montreal, Quebec, Canada

Application December 3, 1937, Serial No. 177,974
In Canada December 3, 1936

7 Claims. (Cl. 226—111)

The present invention relates to improvements in bottle filling valves and more specifically to bottle filling valves of the type using counter-pressure air to control the flow of liquid into the bottles.

An object of the invention is to provide in combination with an operating diaphragm an improved liquid valve controlling the supply of liquid flowing from the liquid tank into the filling tube.

A further object of the invention is to provide a bottle filling valve of this nature, the component parts of which are arranged so as to avoid loss of gas from charged liquids flowing through it.

Another object is to provide a valve of the nature described having its operating elements conveniently disposed so as to prevent their obstruction by vegetable fibers from the beverage syrups.

Other objects and advantages will appear in the following specification, and the novel features of the invention will be particularly pointed out in the appended claims.

The invention is illustrated in the accompanying drawing in which:

Figure 1 is a diagrammatic view of a counter-pressure system showing the improved valve in a reduced side elevation.

Figure 2 is a vertical front cross section of the filling valve.

Figure 3 is a side elevation of the liquid control valve operating mechanism.

Figure 4 is a horizontal cross section along the line 4—4 of Figure 3.

Referring more specifically to the drawing A represents the liquid filler tank with the filler valve B projecting into it.

The filler valve B comprises an upper cage casting 10 and a lower cage casting 11 connected by tubes 12. The upper cage casting 10 is provided with a downwardly extending bracket 13 having an opening 14 therein. The operating diaphragm 15 is placed adjacent to the upper cage casting 10 and secured by a cap 16. The cap 16 and the diaphragm 15 form therebetween a chamber 17. Passageways 18 through the upper cage casting 10 connect this chamber with the tubes 12.

The lower cage casting 11 is provided with a bushing 19 which receives the upper end of a filling tube 20 fitted with a valve seat 21. A valve plug 22 adapted to cooperate with the seat 21 is mounted on a rocker arm 23 fulcrumed on a bracket 24 extending upwardly from the cage

casting 11. The end of the arm 23 remote from the plug 22 is pivotally connected to a stem 25 extending upwardly through the opening 14 in the bracket 13 and having its upper end rigidly secured to the diaphragm 15.

An adjustment nut 26 is provided on the upper end of the stem 25. A coil spring 27 acts against an adjustable collar 28 mounted on the stem 25 so that the outer end of the rocker arm 23 remote from the plug 22 is urged downwardly, thus urging the plug 22 upwardly and away from the seat 21.

A tail piece 29 extends downwardly from the lower cage casting 11 to enclose with the latter a chamber 30 connected with the tubes 12 by ducts 31 through the lower cage casting 11. A counter-pressure shut-off valve 32 comprising a tube 33, a head 34 and a resilient seat 35, is disposed upon the filling tube 20, the head 34 thereof being in communication with a compression spring 36. The tube 33 is provided with a relatively large opening 37 and a smaller pressure release opening 38. A filling valve body 39 having a counter-pressure air opening 40 therein is attached to the lower end of the tail piece 29. A resilient seat 41 is disposed within the lower portion of the body 39. A bottle centering bell 42 having a head 43 and carrying a rubber seat 44 is disposed upon the lower portion of the filling tube 20.

Operation

The tank A is filled with a charged liquid subjected to a predetermined amount of air pressure. The opening 40 in the body 39 communicates with the air pressure cylinder C through a pipe 46. The cylinder C has a relatively greater air pressure therein than the air pressure in the tank A.

In Figure 2 the filling device is shown in non-operative position. When a bottle is placed beneath the bell 42 and moved upwardly the bell is raised until the head 43 strikes the lower end of the tube 33. By continued upward movement of the bell 42 the counter-pressure shut-off valve is raised allowing the counter-pressure air to pass from the opening 40 through the opening 37 in the tube 33 and downwardly between the tube 33 and the filling tube 20 into the bottle. The counter-pressure air from the cylinder C is also allowed to pass upward through the openings 31 in the lower cage casting 11 and through the tubes 12 into the chamber 17.

When the air pressure in the chamber 17 becomes sufficiently great to overcome the air pressure within the tank A the diaphragm 15 is

forced downwardly until the adjusting nut 26 strikes the bracket 13. This downward movement causes the upward movement of the valve plug 22 from the seat 21 thus allowing the liquid to pass from the tank A into the filling tube 20. 5

The spring 27 compensates between the relatively small pressure difference acting on the diaphragm 15 to move the valve plug 22 into the open position and the higher pressure difference 10 tending to close the plug 22 onto its seat 21. The tension of the spring 27 may be altered through the adjustable collar 28 to vary the sensitivity of the valve and to balance its rates of opening and closing. The counter-pressure air 15 in the bottle prevents a rapid flow of liquid therein. The closure of the upper end of the tube by means of the valve plug 22 prevents loss of liquid from the tube when the latter is removed from the bottle. 15

20 During the filling operation with devices of this type the filling tube extends downwardly into the bottle so that its bottom end is close to the flavouring syrup. As the charged liquid rises in the bottle the lower end of the filling tube becomes immersed. In the cases where this tube has a valve at its lower end this valve is likely to become clogged or obstructed in operation by pulp fibres present in the liquid. 25

In the present device, the valve is wholly situated 30 above the filling tube so that its working parts are protected and their size less restricted so that a positive closure is ensured for long operating periods. In a device of this nature in which a valve plug is located at the bottom of the filling 35 tube it is usual to provide a non-resilient seating on account of the small space available. Such a seating must be carefully machined so as to cooperate with the valve plug. The location of the valve at the upper end of the filling tube as in the present arrangement makes it possible to employ a resilient valve seating. This is found to be 40 more efficient in practice and when it becomes worn it may easily and economically be replaced. 45

It is a feature of the device that it provides a filling tube free of internal working parts, so that 45 a smooth flow of liquid from the tank to the bottle is ensured. Thus, separation of gas from the liquid, with its attendant disadvantages of foam in the bottle, and lack of sparkle in the product, are measurably reduced. 50

55 By the improved operation of a device of this nature its advantages will readily be observed. A pressure system of this nature is almost wholly dependent upon the positive operation of the diaphragm operated filling valve. If this important mechanism fails the filling operation may be halted while plant and labour are tied up awaiting its rectification.

It will be understood that the above description 60 is explanatory only and that the invention may be modified in various ways within the scope of the claims without departing from the spirit of the invention.

I claim:—

65 1. In a bottle filling valve of the type described, a tank for containing liquid under pressure, a liquid tube in communication with the tank, a liquid valve arranged to engage with the inlet end of said tube for stopping the flow of a liquid under 70 pressure thereto, an operating diaphragm in communication with the tank and a counter-pressure air chamber, an operating stem connecting the diaphragm with the liquid valve whereby pressure in the tank acts through the diaphragm to 75 close the liquid valve, means urging the liquid

valve towards the open position, a counter-pressure air inlet, a valve for said inlet, a valve sleeve having an inlet and an outlet opening therethrough, shiftable means arranged to be actuated by a bottle for moving said sleeve and said valve whereby the counter-pressure air may pass from said inlet through said inlet opening in said valve sleeve and into the bottle and into the counter-pressure air chamber whereby the diaphragm is actuated to open the liquid valve, the outlet opening in said sleeve being positioned to allow a portion of the air pressure to pass therethrough from said bottle and the counter-pressure air chamber for closing the liquid valve and gradually releasing the pressure from the liquid after a portion of the liquid has passed through said liquid tube. 10 15

2. In a bottle filling valve of the nature described, a liquid tank and an air supply, a liquid tube in communication with said tank, an operating diaphragm in communication with said air supply and with said tank, a valve arranged to engage with the inlet end of said tube, and an operating stem connecting said valve with said diaphragm whereby pressure in the tank acts through the diaphragm to urge the valve to close 20 off the liquid tube from the tank, and means urging the valve towards the open position. 25

3. In a bottle filling valve of the nature described, a liquid tank and an air supply, a liquid tube in communication with said tank, an operating diaphragm in communication with said air supply and said tank, a valve seat arranged at the inlet end of said tube, a rocker arm adjacent to said tube, a valve plug mounted on one end of said arm and adapted to cooperate with said 30 valve seat, and an operating stem connecting the other end of said arm with said diaphragm whereby pressure in the tank acts through the diaphragm to urge the valve plug toward the valve seat, and resilient means urging the valve towards 35 the open position. 40

4. In a bottle filling valve of the nature described, a liquid tank and an air supply, a liquid tube in communication with said tank, an operating diaphragm in communication with said air supply and with said tank, a valve arranged to engage with the inlet end of said tube, an operating stem connecting said valve with said diaphragm, and a spring urging said valve toward its open position. 45

5. In a bottle filling device of the nature described, a liquid tank and an air supply, a bottle entering liquid tube in communication with said tank, an operating diaphragm in communication with said air supply and said tank, a valve seat arranged at the inlet end of said tube, a rocker arm mounted adjacent to said tube, a valve plug mounted on one end of said arm for cooperation with said valve seat, an operating stem connecting the other end of said arm with said diaphragm, a collar mounted on said stem, and a compression spring in engagement with said collar and a rigid bearing to urge said valve toward its open position. 55 60

6. In a bottle filling valve of the type described, a tank for containing liquid under pressure and a counter-pressure air supply, a liquid tube leading from the tank, an operating diaphragm in communication with the tank and the counter-pressure air supply, a valve seat arranged at the 70 inlet end of the tube, a rocker arm adjacent to the tube, a valve plug mounted on one end of the rocker arm and adapted to cooperate with the valve seat to form a closure for the tube, an operating stem connecting the other end of the 75

arm with the diaphragm whereby pressure in the tank acts through the diaphragm to urge the valve plug to close against the valve seat, and a spring on the operating stem arranged to urge 5 the valve plug away from the valve seat to counterbalance the valve closing urge of the diaphragm.

7. In a bottle filling valve of the type described, a tank for containing liquid under pressure and 10 a counter-pressure air supply, a liquid tube leading from the tank, an operating diaphragm in communication with the tank and the counter-pressure air supply, a valve seat arranged at the

inlet end of the tube, a rocker arm adjacent to the tube, a valve plug mounted on one end of the rocker arm and adapted to cooperate with the valve seat to form a closure for the tube, an operating stem connecting the other end of the rocker arm to the diaphragm whereby pressure in the tank acts through the diaphragm to urge the valve plug against the valve seat, a collar mounted on the operating stem and a spring on the stem bearing against the collar to urge the valve 10 plug away from the valve seat. 5
